UNITED STATES PATENT OFFICE.

CHARLES I. MINKOFF AND LOUIS KRONTHAL, OF NEW YORK, N. Y.

CAP.

1,040,727.

Specification of Letters Patent.

Patented Oct. 8, 1912.

Application filed February 24, 1912. Serial No. 679,788.

To all whom it may concern:

Be it known that we, CHARLES I. MINKOFF and LOUIS KRONTHAL, citizens of the United States, and residents of the city of 5 New York, borough of Manhattan, in the county and State of New York, have invented a new and Improved Cap, of which the following is a full, clear, and exact description.

10 Our invention relates generally to caps and more particularly to adjustable caps, such as disclosed in the United States Letters Patent No. 1,014,505, issued to us on January 9, 1912.

15 The principal object of our invention is to provide a new and improved cap, the construction and arrangement being such that one size of the cap may be worn by persons requiring caps of different sizes.

20 A further object of our invention is to provide a cap, the construction and arrangement thereof being such that the cap will be securely held in position on the head.

25 Other objects and advantages of the invention will appear as the description thereof proceeds, the new and useful features being set forth in the appended claims.

30 Reference is to be had to the accompanying drawings forming a part of this specification in which similar characters of reference denote corresponding parts in all the views, and in which—

35 Figure 1 is a perspective view of the cap embodying our invention; Fig. 2 is a bottom plan view thereof, and Fig. 3 is a partial plan view showing a modified construction.

40 While the cap shown in the drawings embodies what is popularly known as a golf cap, it is, of course, obvious that the construction herein described and claimed may be applied to caps bearing different names, all of which, however, are designed to be worn as a head covering.

45 The body 1 of the cap may be made of any desired size and material and is so constructed of a number of parts that the ends of these parts form a substantially circular opening, a portion of the cap adjacent this opening being provided with a band 2; it is 50 to be particularly noted that this band does not extend throughout the periphery of this opening but that the ends 2^a, 2^b, of the band terminate remote from each other, as shown particularly in Fig. 2.

55 The ends 2^a, 2^b, of the cap band are con-

nected together through the medium of a resilient band 3, the ends of which are suitably secured to the ends 2^a, 2^b, in any suitable manner, preferably by being stitched thereto.

60 Extending around the outside of the band 2 and the resilient element 3 is an auxiliary element 4 which may be termed an overlapping band, the ends 4^a, 4^b, of this element terminating remote from each other, 65 the ends, however, being connected together with a resilient element 5 secured to the ends 4^a, 4^b, in any suitable manner, preferably by being fastened thereto by means of suitable buttons 6 or equivalent construction. The 70 intermediate portion of this overlapping band 4 is secured to the intermediate portion of the resilient element 3 in any suitable manner, preferably by means of stitching 7; the second or auxiliary, or overlapping band 75 is held in position on the cap in any suitable manner, preferably by means of straps or bands 8 which are sewed in position.

80 Referring particularly to Figs. 1 and 2, it will be noted that the particular form of cap herein described is provided with a vizor 9, the vizor being secured to the first band 2 which is carried by the cap, the resilient element 5 being preferably adjacent the vizor, while the other resilient element 3 is 85 preferably diametrically opposite at the rear of the cap.

85 The cap, as described, may be worn by persons requiring caps of different sizes inasmuch as the elements 3 and 5, being resilient 90 in their nature, enable the periphery of the open portion of the cap to be securely positioned on heads of different sizes. By this construction we are enabled to provide a cap of a single size which will displace caps 95 of sizes smaller and larger than such cap, the result being that the stock necessarily carried by a dealer need not be made up of so many different sizes. It is also clear that a cap of this construction, by reason of its 100 expandible feature, may be securely fitted on the head and is particularly adapted for outdoor use in windy weather, the cap not being easily displaced from the head.

105 Referring particularly to Fig. 3, a modification is set forth, varying in a certain detail from that previously described. In this modified form of construction, the resilient element 3 is unsecured to the second or overlapping band 4 of the cap, the adjacent por- 110

tions of these elements being held in place by means of a band or strap 8^a which differs in no material respect from the band or straps 8 previously described. Thus, when 5 using the cap embodying this modification, it is positioned on the head in the same manner as the form first described and, as far as its operation is concerned, differs in no substantial respect therefrom.

10 Having thus described our invention, we claim as new, and desire to secure by Letters Patent:—

1. A cap comprising a body having an opening therein, whereby the cap may be positioned on the head, the cap being provided with a band secured thereto adjacent the said opening, the ends of the band being remote from each other, the said ends being connected together by means of a resilient 15 element suitably secured to the said ends, together with a second or overlapping band extending around the said resilient element and portions of the first band, the said resilient element being secured to this second 20

band, together with a resilient element connecting the ends of the second band. 25

2. A cap comprising a body having an opening therein whereby the cap may be positioned on the head, the cap being provided with a band secured thereto adjacent the 30 said opening, the ends of the band being remote from each other, the said ends being connected together by means of a resilient element suitably secured to the said ends, together with a second or overlapping band 35 extending around the said resilient element and portions of the first band, a resilient element connecting the ends of the second band, together with straps carried by the cap for maintaining the second band in position. 40

In testimony whereof we have signed our names to this specification in the presence of two subscribing witnesses.

CHARLES I. MINKOFF.
LOUIS KRONTHAL.
